UNITED STATES PATENT OFFICE.

THOMAS DODDRELL, OF SLOUGH, ENGLAND.

CLAMP FOR DRAWING TOGETHER WOODEN JOINTS.

SPECIFICATION forming part of Letters Patent No. 488,546, dated December 27, 1892.

Application filed November 12, 1891. Serial No. 411,682. (No model.) Patented in England November 27, 1889, No. 19,052; in France December 14, 1889, No. 33,079; in Belgium December 31, 1889, No. 88,867, and in Germany June 18, 1890, No. 52,387.

To all whom it may concern:

Be it known that I, THOMAS DODDRELL, a subject of the Queen of Great Britain, residing at Slough P. O., in the county of Buckingham, England, have invented a new and useful Improved Clamp for Drawing Together Wooden Joints, (for which I have obtained patents in the following countries: Great Britain, No. 19,052, bearing date November 27, 1889; Belgium December 31, 1889, No. 88,867; Germany June 18, 1890, No. 52,387; France December 14, 1889, No. 33,079,) of which the following is a specification.

Figure 1 represents a front elevation with the pieces of timber to be joined together broken off at the ends. The straps are broken off for want of space; Fig. 2 is a side elevation.

My invention comprises a screw bolt *b* about four inches long with a winged nut *d* the point of the screw to be reduced so as to form a shoulder. A washer and a small iron plate *e* are fitted easy to the reduced point to withstand the pressure and so form a flat bearing on the article to be joined. At the other end of the screw is a hole through which a steel pin *a* is passed for the purpose of screwing up.

c c are two strips of iron with holes *i* about two inches apart up the center, the top hole being oval shaped so as to hang easy on the wings *d* of the nut. A block of hard wood *h* with a steel pin *j* wedged through it eccentric from the top and bottom edges and the ends of the pin to project about an inch each side of the block *h*. The ends of the pin *j* are inserted in the

corresponding holes *i* of the strips of iron *c*, *c*, and the block turned either the thick or thin side up according to the breadth of the articles *g*, *g*, to be joined. The screw bolt *b* can now be screwed up and the articles *g*, *g*, which rest on the block *h* and between the iron strips *c*, *c*, will be drawn together equally on each side, and even if the joint or joints have not been properly prepared it will nevertheless draw up true, the prepared surfaces adapting themselves to each other. It is not necessary that the iron strips *c*, *c*, or side pins should be over three feet long as several can be joined together with a small nut and bolt. The clamp can be made to any size or strength.

What I claim, and desire to secure by Letters Patent of the United States, is—

The combination of the screw bolt with the washer and iron plate fitted to the reduced point, and the steel pin passed through the hole in the other end, the winged nut with the perforated iron strips hung thereon, and the stationary block against which the work is forced with the steel pin wedged through it for drawing together wooden joints, substantially as herein described and according to the accompanying drawings.

THOMAS DODDRELL.
